SUBMERGED BARGE AND TOWBOAT

Morris Katcher and Stanley W. Walker,
New York, N. Y.

Application October 28, 1942, Serial No. 463,662

17 Claims. (Cl. 114—235)

This invention relates to a combined submarine barge and its tow boat. It is an object of the invention to provide a means of water transportation which is less vulnerable to torpedoes than the present surface cargo bearing vessels especially those of large size. The tow boat of the combination is a surface craft which is kept as small as possible for the pulling power required of it. Further it is made as shallow of draft as is consistent with stability and navigability. The smaller the craft the more difficult a target it is. Further, torpedoes are usually sent out at a substantial depth to avoid the disturbance of wave action. A torpedo running ten feet or less below the surface is apt to "porpoise," that is, to leap out of the water and lose direction. Consequently, a craft of shallow draft will be higher than the normal torpedo path making it hard to hit. While torpedoes are sent out at a substantial depth, the latter cannot be too great. By causing the barge to be towed at a depth greater than the normal torpedo path, it will be hard to hit. Further, it will be difficult, especially in the case of a submarine, to determine the depth of the barge and its distance behind the visible tow boat. The small amount of moving machinery on the barge makes its location difficult to find by sound detecting devices.

It is an object of the invention to provide means for keeping the barge at a predetermined level. Other means are provided to keep the barge on an even keel. A releasable buoy is provided which rises to the surface should the tow cable break or even if the barge sinks to too great a depth. The buoy carries with it an air line which can have air pumped into it from the tow boat for raising the barge. A number of alternate constructions are provided for steering the barge beyond that which would normally be produced by the inclination of the tow connection. Under certain conditions, especially in a tortuous channel, it may be necessary to give extra steering action to the tow connection. A manually operated device is provided for the extra steering. In another form, the tow connection is provided with an air hose extending from the tow boat to supply the air needed for the barge especially where a crew is stationed on the barge. An electric cable is also provided for the tow connection. Where a crew is stationed on the barge, the depth controlling means, as well as the means for keeping the barge on a predetermined keel, need not be automatic but can be controlled by the crew.

Another advantage of the combination of tow

boat and submarine barge is that cylindrical barges can be made in a boiler shop with less labor and metal used in their construction than cargo surface vessels. Wood could also be used for both the barge and its tow boat.

Other objects and advantages will become apparent upon further study of the description and drawings, in which—

Fig. 1 is an elevation of the submarine tow, only the rear portion of the tow boat being shown.

Fig. 2 is a plan view of the tow using a double tow line, only the rear portion of the tow boat being shown and the handwheel at the turntable for manual steering of the barge being omitted.

Fig. 3 is a plan view, as in Fig. 2, to a smaller scale, showing the submarine barge steered manually beyond that normal for the tow lines.

Fig. 4 is a front elevation of the submarine barge of Fig. 1.

Fig. 5 is a plan view of the tow, only the rear portion of the tow boat being shown. A single tow line is used engaging front rudders on the barge. The utility connection or cable is broken away so as to expose the tow line.

Fig. 6 is an elevation of the barge portion of Fig. 5 and also shows a portion of the tow connection.

Fig. 7 is a plan of a portion of the barge of Fig. 6 showing the tow line acting upon one of the rudders.

Fig. 8 is a plan of the barge of a tow, using a single tow line which operates rear rudders on the barge.

Fig. 9 is an elevation of the barge of Fig. 8.

Fig. 10 is an elevation, to a larger scale, partially in section of the barge of Fig. 1.

Fig. 11 is a section taken along the line 11—11 of Fig. 10.

Fig. 12 is a plan, partially in section of the barge of Fig. 10.

Fig. 13 is a vertical longitudinal section of the barge at the buoy hatch and control.

Fig. 14 is an elevation of the tow, the rear portion only of the tow boat being shown, with the barge sunken below a predetermined depth and the buoy released. A portion of the tow connection is parted.

Fig. 15 is an enlarged detail of the valve which effects the raising of the barge when it sinks beyond a predetermined depth.

Fig. 16 is an enlarged detail of the valve which effects the lowering of the barge when it rises above a predetermined level, and

Fig. 17 is a diagram of the electrical connections of the tow.

Mounted on tow boat 20, Figs. 1, 2, 3 and 4 near its stern is a turntable 21 which is rotatable about pivot 22. Winches 23 and 24 are mounted on turntable 21. A portion of the periphery of turntable 21 is provided with gear teeth 25 which are engaged by the teeth of gear 26 fixedly mounted near the bottom of shaft 27. The upper end of shaft 27 is provided with handwheel 28 for manually operating gear 26 and thereby turning turntable 21 about its pivot 22. A tow line 29 extends from winch 23, through eye 31, through the eye of outrigger arm 33 on submarine barge 37 to its connection with trunnion 35. Another tow line 30 extends in a similar manner from winch 24, through eye 32, through the eye of outrigger arm 34 to its connection with trunnion 36 on the opposite side of barge 37 from trunnion 35. Another winch 38 is carried on tow boat 20 at its stern. An electric cable 39 extends from winch 38 to barge 37. While shown diagrammatically as a single line, cable 39 has lashed to it an air line or hose which extends from tow boat 20 to barge 37 for supplying air to the latter as needed. The two tow lines 29 and 30 with cable 39 and with or without its air hose are covered by the comprehensive expression "tow connection." Outrigger arms 33 and 34, Fig. 4, are pivotally mounted on barge 37. For a purpose to be explained later on, they suspend the bow of barge 37 on tow lines 29 and 30, and yet let the latter assume various inclinations laterally, that is, in a horizontal projection, with the longitudinal axis of barge 37 as shown in Fig. 3.

The use of two tow lines and their particular connections and engagements are for the purpose of inducing barge 37 to respond more readily and certainly to the steering of tow boat 20 than would an ordinary single tow line connecting the stern of the tow boat with the bow of the barge. Our construction is such that during turning of the tow boat, the barge is turned nearer to parallelism with said boat than a theoretical line extending between the bow of the barge and the stern of the boat. When tow boat 20 is turned, as in Fig. 3, trunnion 36 is pulled forward more than trunnion 35, causing the barge to move toward parallelism with the tow boat. Arm 34 swings out to accommodate tow line 30, while arm 33 swings in. Arm 33 must swing in enough, at its eye, toward the longitudinal axis of the barge not to interfere too much with the inclination of tow line 29. Arm 33 as shown does interfere to some extent, but the interference is within practical limits. It will be readily understood that the amount of interference can be reduced if desired by curving the arm more so as to bring its eye nearer to the longitudinal axis of the barge. What was said of arm 33, of course, also applies to arm 34.

In tight places it may be desirable to turn barge 37 more than is normal to the tow connection just described. This is accomplished by rotating turntable 21 by means of handwheel 28, shaft 27 and gear 26. Such a condition is shown in Fig. 3.

The alternate form of tow connection shown in Figs. 5, 6 and 7 uses only one tow line 43 and has rudders 50 and 51 at its bow. At boat 20, line 43 is mounted on winch 40, while at barge 37, aft of pins 41 and 42, it is divided into two branches 44, the branches being attached to trunnions 35 and 36. Branches 44 pass through

5 a yoke 45 which permits them to be displaced laterally as can be seen by comparing their positions in Fig. 5 with their positions in Fig. 7. The forward portion of barge 37 also bears down on branches 44 through the agency of yoke 45. This bearing down action is similar to that which occurs between tow lines 29 and 30 and outrigger arms 33 and 34 in Figs. 1, 2 and 3. Pin 41 extends upward from lever 46, the latter being pivoted to the barge at 48. The outer end of lever 46 is in the form of a rudder 50. Pin 42 extends upward from lever 47 which is pivoted to the barge at 49. The outer end of lever 47 is in the form of a rudder 51. When tow line 43 is inclined as shown in Fig. 7 due to the turning of the tow boat to port, not shown, it engages pin 41 causing rudder 50 to be extended. This causes barge 37 to reduce its inclination to tow line 43 by swinging its bow to port resulting in the barge assuming a position more nearly parallel to that of the tow boat than would normally be the case if the tow line acted without the intermediation of the rudder. It will be readily understood that the barge will be caused to steer to starboard if the inclination of tow line 43 is reversed from that shown in Fig. 7 and engages pin 42.

The alternate form of tow connection shown in Figs. 8 and 9 also uses only one tow line 43 with branches 44 connected to trunnions 35 and 36. Tow line 43 on its way to its branches passes between pins 52 and 53. Pin 52 extends downward from lever 54, while pin 53 extends downward from lever 55. Both levers are pivoted on pivot pin 56. Pivoted mounted on the stern of barge 37 is a rudder 57 having a king post 58. Arms 59 and 60 are fixed to the upper end of post 58. A line 61 extends from arm 59 forward through eye 62 to the rear of lever 54, 40 while a line 64 extends from arm 60 forward through eye 63 to the rear of lever 55. When tow line 43 is inclined to port, as shown in dot and dash lines, by the steering of the tow boat, it pushes pin 52 to port turning lever 54 counterclockwise. This causes a pull on line 61 and on arm 59 effecting the turning of rudder 57 to port, as shown by the dot and dash lines. The barge is thereby steered to port by its rudder causing it to lessen its inclination with the tow line. 45 This causes the barge to assume a position more nearly parallel to that of the tow boat (not shown) than would normally be the case if the tow line acted without the intermediation of the rudder with its harness. It will be readily understood that the barge will be caused to steer to starboard if the inclination of tow line 43 is reversed from that just described. Branches 44 of the tow line pass through a yoke 65 which permits them to be displaced laterally. The forward portion of barge 37 bears down on branches 44 through the agency of yoke 65. This bearing down action is similar to that which occurs between tow line 29 and 30 and outrigger arms 33 and 34 in Figs. 1, 2, and 3, and the action of yoke 45 on tow line 43 in Figs. 5, 6 and 7. Pivot pin 56 extends upward from platform 134 which is carried by yoke 65.

For efficient operation of the tow, the barge must among other things have a minimum tendency to roll. To accomplish this fins 66 and a keel 67 are provided, Figs. 10, 11 and 12. Further, the barge must not pitch too much and remain on even keel. The fins prevent pitching to a certain extent. In order further to increase the stability of the barge, counterweight

mechanism is provided to keep the barge on even keel. Said mechanism further is set so that the barge will have a predetermined normal keel which will cause it to bear down in its fore portion on the tow connection. How the fore portion of the barge bears down on the tow connection has already been described in connection with outrigger arms 33 and 34 and yokes 45 and 65.

In a compartment 68 provided in the upper portion of barge 37 are located longitudinal ways 69 upon which a counterweight 70 is adapted to ride. Projecting down from counterweight 70 is an internally threaded eye 71 which engages rotatably mounted screw bar 72. Screw 72 is in the nature of a lead screw on an engine lathe, its rotation in one direction sending counterweight 70 fore, and in another direction, aft, along ways 69. Gear 73 is fixed to screw 72. It is driven by gear 74 in turn driven through reduction gearing on reversible electric motor 75. A level switch 76, Fig. 17, is located at a convenient place, not shown on the barge. A number of different types of level switch could be used, but the particular one shown is a pendulum type, the pendulum weight 81 having a weighted bar 82 fixed to it and pivoting about a pin 83. When the bow of the barge tilts downward, insulating lug 77 closes two pole switch 79 against spring 135, completing the circuit from source wire 84, through switch 79 through wire 85, through motor 75, out through wire 86 through switch 79 to source wire 87. With the circuit thus closed, motor 75 rotates screw 72 to send counterweight 70 aft until the barge has its bow tilted up sufficiently to withdraw lug 77 from switch 79, allowing the latter to open. Conversely if the bow of the barge tilts up too much, lug 78 closes switch 80, against spring 136 completing the circuit from source wire 84, through switch 80 into wire 88, thence through wire 86, motor 75, wire 85, wire 89, switch 80, wire 90 to source wire 87. With the circuit thus closed, motor 75 rotates screw 72 to send counterweight towards the bow of the barge until said bow tilts down enough to withdraw lug 78 from switch 80, allowing the latter to open. The gaps between lugs 77 and 78 and their switches 79 and 80, with bar 82 level, can be set different, one from the other as predetermined, so that the barge will ride at a predetermined normal keel, not necessarily level. Current may be provided for the motor by a battery on the barge, or from the tow boat, through cable 39 of the tow connection.

As a further means for maintaining the stability of the barge, an air compartment 91, Fig. 10, is provided fore and aft. Cargo is carried in compartments 92. In the particular embodiment of the barge shown, oil is the cargo, pipe 93 being used to distribute the oil to the various cargo compartments 92. A hatch 94 is provided for entrance into the barge.

Means for maintaining the barge at a predetermined depth will now be described. It consists essentially of a valve 95 set to admit air under pressure into a ballast tank 98 to discharge water therefrom when the barge sinks too low and of another valve 108 to let out the air from the tank through pipe 115 and admit water thereby when the barge rises too high. Valve 95, Figs. 10 and 15, acts to admit air, through pipe 97 from air tank 96 into ballast tank 98 when the barge sinks too low, the admission of air under pressure forcing out water through discharge nozzle 99 from the latter tank. Valve 95

5 consists of a disc 100 fixed to the outer end of valve rod 101 and held out by compression spring 102 substantially flush with the sides of barge 37. The spring, valve rod and disc are set in a pocket 103. To limit the travel out of disc 100 and to calibrate the compression of spring 102, nut 104 at the outer limit of movement of the valve engages inner wall 105 of pocket 103. Valve disc 100 is set in flexible diaphragm 106 of the Sylphon type, said diaphragm being in watertight connection with the disc and the wall of the barge preventing water from entering pocket 103. Valve rod 101 passes through pipe 97, normally blocking it off, but when the barge sinks beyond a predetermined depth, the water pressure will force disc 100 and said rod inward to bring port 107 across said pipe, permitting the air from pressure tank 96 to enter ballast tank. This will force water out of the latter tank, lightening the barge thereby and hence causing it to rise.

Valve 108, Fig. 16, is similar in construction to valve 95. It operates in a pocket 109 set in the side of the barge. A disc 110 is set in a Sylphon diaphragm 111 and is mounted on the end of valve rod 112. Compression spring 113 acts to force out disc 110, but as shown in the picture, said disc and diaphragm are subjected to water pressure which hold them back in pocket 109. Nut 114 limits the outward movement of valve rod 112. Valve rod 112 passes through pipe 115 (not shown in Fig. 16) in a manner similar to that which valve rod 101 passes through pipe 97. A port, not shown, is provided in valve rod 112 similar to port 107 in rod 101. With the valve in the position shown in Fig. 16, valve rod 112 blocks off pipe 115, permitting no air to escape from ballast tank 98, and hence no water can enter said tank through nozzle 99. However, when barge 37 rises above a predetermined depth, the water pressure is relieved on disc 110 and diaphragm 111, and they are consequently pushed out by spring 113, bringing the port, not shown, in valve rod 112 opposite pipe 115 just as port 107 of rod 101 is brought opposite pipe 97. With pipe 115 thus opened, air is allowed to escape from ballast tank 98 allowing water to enter said tank, increasing the weight of the barge thereby and hence causing it to sink.

50 When there is no air line extending from tow boat 20 to barge 37 along cable 39 of the tow connection as previously described, air tank 96 must have enough air to have sufficient pressure to overcome the water pressure at the maximum predetermined depth. Where there is an air connection, the pressure in tank 96 can be maintained from a compressor on the tow boat.

A salvage buoy 116 is provided, Figs. 10, 13 and 14, which would be released, should the tow connection part. The parting of the tow connection would break cable 39. Buoy 116 is also released should the barge get out of control and sink too deeply even if the tow connection is not broken.

65 A buoy compartment 117 is provided on the barge, said compartment having a hinged and perforated hatch cover 118, normally held closed against the buoyancy of buoy 116 by hook 119 at the upper end of pivoted armature lever 120. See also Fig. 17. As long as cable 39, leading to the source of power, remains unbroken, current will flow through electromagnet 121, holding hook 119 in position against the pull of spring 122 to lock hatch cover 118. However, should cable 39 become broken, spring 122 will pull hook 119 away from hatch cover 118 allowing buoy 116 to rise.

Attached to buoy 116 by a rope 123 is an air hose 124 connected at its lower end (not seen) to the upper part of ballast tank 98. The upper end of hose 124 is provided with a valve 125 for shutting it off. Once the buoy rises to the surface, the location of the barge can be had, and the latter brought to the surface by pulling up hose 124 and forcing air into it from the tow boat after opening valve 125. It is to be noted, however, that when barge 37 rises beyond a predetermined depth, valve 108 would permit air to escape from the top of ballast tank 98 and render useless the forcing of air into hose 124. In order to prevent this, valve 108 is locked in inoperative position by means of forked bar 121, Figs. 16 and 17, which bar moves in between nut 114 and wall 126 of pocket 109. The interposition of bar 127 between nut 114 and wall 126 is effected by the pull of spring 128 on pivoted armature lever 129. Armature lever 129 was released when cable 39 broke, because then the current was interrupted through electromagnet 130.

The release of buoy 116 when the barge drops too deep is effected, even without the breaking of cable 39, through the agency of valve 131, which is similar in action to valve 95, except that when the water pressure becomes too great, disc 132 is pushed in by said pressure opening switch 133. The opening of switch 133 deenergizes magnets 121 and 130 releasing buoy 116 as described above when cable 39 was broken, and locking valve 108.

We claim:

1. In combination, a tow boat, a submarine barge, a tow connection connecting the boat and the barge, means for maintaining the barge at a predetermined depth, means for maintaining the barge at a predetermined keel, the barge at its forward portion riding the tow connection, being held up thereby at said portion higher than normal for said predetermined keel.

2. In combination, a tow boat, a submarine barge, a tow connection fastened at its forward end to the boat and at its rear to the barge at a substantial distance aft of its bow, said connection, during turning of the boat, turning the barge nearer to parallelism with the boat than a theoretical line extending between the bow of the barge and the stern of the boat, means for maintaining the barge at a predetermined depth and at a predetermined keel, and means on the forward portion of the barge engaging said connection holding up the forward portion of the barge thereby higher than normal for said predetermined keel.

3. In combination, a tow boat, a submarine barge towed by said boat, a water ballast tank on the barge, means actuated by the water pressure in accordance with the depth of the barge to effect the discharge of water from the tank when the barge sinks to a predetermined level and to effect the admission of water into the tank when the barge rises to a predetermined level.

4. In combination, a tow boat, a submarine barge towed by said boat, a water ballast tank on the barge, a source of air pressure, valve means actuated by the water pressure to admit air from said source into the ballast tank to force out water therefrom when the barge reaches a predetermined maximum depth, and other valve means actuated by the water pressure to permit escape of air from the tank and the consequent admission of water when the barge reaches a predetermined minimum depth.

5. In combination, a tow boat, a submarine

barge, a tow connection, connecting the boat and the barge, means for maintaining the barge at a predetermined depth, a releasable buoy carried on the barge and means actuated by the breaking of the tow connection for releasing the buoy.

6. In combination, a tow boat, a submarine barge, means for maintaining the barge at a predetermined depth, a releasable buoy carried on the barge, electrically controlled means on the barge for releasing the buoy, a tow connection connecting the boat and the barge, said tow connection providing an electrical connection between the electrically controlled means and the boat, the breaking of the tow connection breaking said electrical connection, actuating thereby the buoy releasing means to release the buoy.

7. In combination, a tow boat, a submarine barge, a tow connection fastened to the boat and to the barge aft of its bow, means controlled in accordance with the deviation of the slope of the keel of the barge from a predetermined normal slope, a weight mounted on the barge to move fore and aft, mechanism for sending the weight fore and aft, the actuation of said mechanism being effected by said deviation controlled means to send the weight fore or aft to incline the keel to correct its deviation from normal, said barge when at said normal slope having its forward portion bear down on the tow connection.

8. In combination, a tow boat, a submarine barge towed by said boat, means for maintaining the barge at a predetermined depth, a releasable buoy carried on the barge, electrically controlled means for releasing the buoy, an electric cable extending between the boat and the barge and in electrical connection with said means, the breaking of the cable actuating said means to release the buoy.

9. In combination, a tow boat, a submarine barge, a tow connection fastened to the boat and to the barge at a location a substantial distance aft of its bow, means for maintaining the barge at a predetermined depth, and means for maintaining the center of buoyancy of the barge forward of said location, the forward portion of the barge riding said connection and bearing down thereon.

10. In combination, a tow boat, a submarine barge, means for maintaining the barge at a predetermined depth, and a tow connection fastened to the boat and the barge, said connection, during turning of the boat, turning the barge nearer to parallelism with the boat than a theoretical line extending between the bow of the barge and the stern of the boat.

11. In combination, a tow boat, a submarine barge, a pair of tow lines connecting the barge to the boat, each tow line engaging the boat and the barge at a substantial transverse distance from the longitudinal axis of each, the engagement of each line being on an opposite side of the longitudinal axis from the other, the engagement of each line to the barge being also at a substantial distance aft of its bow, means for maintaining the barge at a predetermined depth and keel, and means on the forward portion of the barge contacting the tow lines, said latter means permitting transverse movement of the tow lines with respect to the barge while holding up the forward portion of the latter.

12. In combination, a tow boat, a submarine barge, a turntable mounted substantially at the stern of the boat, a pair of tow lines, the forward end of each line being connected to the tow

boat, said end engaging the turntable and extending well out transversely from the longitudinal axis of the tow boat and on an opposite side thereof from the other line, the rear end of each line being connected to the barge on opposite sides thereof from the other, at a substantial distance transversely from its longitudinal axis, the connection of each line to the barge being at a substantial distance aft of its bow, manually operated means for effecting the turning of the turntable about its pivotal axis, means for maintaining the barge at a predetermined depth and keel, and means on the forward end of the barge engaging the tow lines, said latter means permitting transverse movement of the tow lines with respect to the barge while holding up the forward portion of the latter.

13. In combination, a tow boat, a submarine barge, a tow line connected at its forward end to the boat and at its rear to the barge at a substantial distance aft of the bow of the latter, a pair of rudders pivotally mounted at their forward portion on the barge at its forward portion, a rudder on each side thereof, the tow line on its way from the barge to the boat engaging the rudders, said tow line when inclined to the port of the barge by the steering of the boat causing the starboard rudder to be extended and when inclined to the starboard of the barge causing the port rudder to be extended.

14. In combination, a surface tow boat, a submarine barge towed by said boat, gravity actuated mechanism controlled in accordance with the deviation of the slope of the keel from a predetermined normal slope, a weight mounted to be shifted fore and aft controlled by said mechanism to incline the keel to correct its deviation from normal, a water ballast tank on the barge and means actuated by the water pressure in accordance with the depth of the barge to effect the discharge of water from the tank when the barge sinks to a predetermined level and to effect

the admission of water into the tank when the barge rises to a predetermined level.

15. In combination, a tow boat, a submarine barge, a tow connection fastened to the boat and the barge aft of its bow, means controlled in accordance with the deviation of the slope of the keel of the barge from a predetermined normal slope, mechanism on the barge to effect a change of slope of the keel, the actuation of said mechanism being effected by said deviation controlled means to incline the keel to correct its deviation from normal, said barge when at said normal slope having its forward portion bear down on the tow connection.
16. In combination, a tow boat, a submarine barge, means for maintaining the barge at a predetermined depth, a pair of tow lines connecting the barge to the boat, each tow line engaging the boat and the barge at a substantial transverse distance from the longitudinal axis of each, the engagement of each line being on an opposite side of the longitudinal axis from the other, and means on the boat for varying the length of the tow lines independently of each other for varying the horizontal inclination of the barge with respect to the boat.

17. In combination, a tow boat, a submarine barge, means controlled in accordance with the depth of the barge for maintaining the barge at a predetermined depth, a pair of tow lines connecting the barge to the boat, each tow line engaging the boat and the barge at a substantial transverse distance from the longitudinal axis of each, the engagement of each line being on an opposite side of the longitudinal axis from the other, said tow lines, during the turning of the boat, turning the barge nearer to parallelism with the boat than a theoretical line extending between the bow of the barge and the stern of the boat.

MORRIS KATCHER.
STANLEY W. WALKER.
